UNITED STATES PATENT OFFICE.

THOMAS B. LAYCOCK, OF INDIANAPOLIS, INDIANA.

CASEMENT WINDOW.

Application filed June 22, 1925. Serial No. 38,648.

French casement windows, bearing small panes of glass, are popular in building construction and would be still more so were it not for the inconvenience of washing the small panes to keep them clean. One of the objects of this invention, therefore, is so to construct the window that the glass will be in one or two large lights, which can be swung on hinges far enough away from mullions on each side to allow unobstructed access to the lights for cleaning and polishing them as large panes of glass.

A further object is to make the lights vertically adjustable to provide openings at the top or bottom of the window for purposes of ventilation without swinging the window open on its hinges.

Another object is to provide fixed metal mullions on the outside of the glass, which, besides conforming in appearance to the mullioned effect of the window, will constitute a barrier to repel burglars and other trespassers.

Another object is to provide an inexpensive fly screen which can be conveniently placed and removed.

A further object is to simplify and better the construction in ways that will be hereinafter explained and the novel features thereof specified in the appended claims.

I accomplish the objects above enumerated by means of the accompanying drawing which is expressly made a part hereof and in which—

Fig. 1 is an inside elevation of my invention in closed condition, Fig. 2 is a perspective view of the same in open condition, Fig. 3 is a vertical section on the line 3—3 of Fig. 1, and Fig. 4 is a perspective view of a pane of glass and a portion of its mounting.

Like characters of reference indicate like parts in the several views of the drawing.

The window frame 5 is here shown as formed of a sheet metal shell with a wood filling which is set in a wall in the usual manner. It has an inner rabbet forming a shoulder 6, which acts as a stop to limit the outward adjustment of the window.

The window as a unit comprises three main separate members, i. e., an outside metal grating which has mullions 7 according to the desired pattern or design. This member is preferably fastened by screws 9, or other secure means to the frame 5 and will form a barrier against the passage of burglars or other trespassers through the

opening. The second member 10 may be of wood, metal or metal filled with wood, and corresponds in dimensions with, and has mullions 8 like the mullions of grating 7, thereby to present the effect when closed of a single French window with mullions. The member 10 is hinged to the frame 5, sufficiently far from the grating 7 for the assembly between the two of the third member, comprising a rectangular frame 11, preferably of hollow sheet-metal construction, as shown in Fig. 4, which is hinged to the member 10, and will swing away from the grating 7 with the member 10, but may afterwards be swung on its own hinges away from said member 10, after releasing a catch 12. As shown, the inner vertical and bottom faces of the frame 11 are provided with a central flange 13 which divides these faces into two slideways for the same number of glass lights 14 and 15, which are enough more than half of the height of the opening in frame 11 to form an overlap, as shown. The space between the lapped ends of the closed lights is closed to keep out dust and cold by a felt or other strip 16 which is cemented to one of the lights. Pivoted fingers 17 are here shown as movable for the assembly or removal of a light, and when lowered in front of the glass they form outer slide ways in which the raising and lowering of the lights is permitted, to secure ventilation without opening the window on its hinges.

Fixed flanges 18 may be used in part, or all of the way up if the top cross bar of frame 11 is recessed as shown at 19, for the insertion of the lights into their slideway through said recesses.

The lights may be balanced by weights sliding in the hollow frame attached to cords which pass over pulleys and are fastened to the lights in the usual construction of balanced sash (not shown) or they may be raised and lowered by knobs 20 attached to the lights and passing out through slots 21 in a vertical mullion of the member 10, or by a cord 21'. My preferred method of cord attachment as illustrated best in Fig. 4, comprises a bar 22 having end hooks 23 that embrace the horizontal edges of the glass and have eye extensions 24 for the attachment of a cord. A bar 25 on a hook at one end has a threaded hole in which a screw or knob 20 is screwed. A given position of the glass is held by tightening the knob against the mullion. A wire cloth 26 is placed

against the inner side of grating 7 to exclude flies and other insects and is removably held by fasteners 27.

From the above description it is apparent that ventilation may be had by raising the bottom light or lowering the top one, or both, without opening the casement window; or the window may be swung open if still more air is desired. It is also seen that the outer grating remains in position at all times, to repel interlopers, and that the opening is effectually screened against the entrance of insects.

It is also apparent that by swinging the middle and outer hinged members away from each other access may be had to both sides of the large glass lights to wash them without interference from the mullions on either side.

20 The inner member 10, with its mullions, may be omitted and the member 11 hinged to the frame 5, so as to swing away from the member 10 for access to the outer sides of the glass for washing, thereby cheapening the cost of construction and retaining most of the advantages as well as the effect of the job, and instead of hinging the member 11 it may be made immovable, but with slide-ways therein for the two lights.

30 The invention is applicable to casement doors as well as to windows.

I claim:

1. In a casement window, an outside fixed mullioned member, in combination with an inner mullioned member having vertical ways, glass lights slidably mounted in said ways and means for removing the mullions from the lights while cleaning the lights.

2. In a casement window, an outside fixed mullioned member, in combination with an inner mullioned member having vertical ways, glass lights slidably mounted in said ways, means for removing the mullions from the lights while cleaning the lights, and an insect screen of wire cloth held by and between said outside and inner members.

3. In a casement window, an outside fixed mullioned member, in combination with an inner mullioned member having vertical glass-light receiving ways and single pane lights slidably mounted in said ways, and means for removably assembling the inner member relative to the outer one and the mullioned portions of the inner member from the lights whereby the members may be separated to avoid interference by their mullions with cleaning and polishing of the glass lights.

4. In a casement window, an outside fixed mullioned member, in combination with an inner mullioned member having vertical glass-light receiving ways and single pane lights slidably mounted in said ways, and

means for removably assembling the inner member relative to the outer one and the mullioned portions of the inner member from the lights whereby the members may be separated to avoid interference by their mullions with cleaning and polishing of the glass lights, and an insect screen of wire cloth removably held by and between the outside and inner members.

5. The combination with a casement window having glass lights and mullions on each side of the lights, of means for freeing the lights from interference of the mullions while cleaning and polishing the lights.

6. In a casement window, a pair of separable members having corresponding mullions, and a glass light carrying member assembled between the mullion carrying members and swingingly separable therefrom for access to both sides of the glass for the polishing and cleaning of the glass.

7. In a casement window, an outer mullioned member, an inner mullioned member movable inwardly, and a middle glazed member movable relative to the other two.

8. In a casement window, an outer mullioned member, an inner mullioned member movable relative to the outer member, a middle member movable relative to both of the other members, and glass lights slidably mounted in the middle member.

9. In a casement window, an outer mullioned member, an inner mullioned member movable relative to the outer member, a middle member movable relative to both of the other members, glass lights slidably mounted in the middle member and means for holding the lights in any given position.

10. In a casement window, an outer fixed mullioned member, an inner mullioned member hinged to swing relative to the outer member, a middle member movable relative to both of the other members and glass lights slidably mounted in the middle member.

11. In a casement window, an outer fixed metal mullioned member, a correspondingly mullioned inner member hinged to swing relative to the outer member, a middle member hinged to swing relative to the outer member, a middle member hinged to the inner member and glass lights slidably mounted in the middle member.

12. In a casement window, an outer fixed metal mullioned member, a correspondingly mullioned inner member hinged to swing relative to the outer member, a middle member hinged to the inner member having two vertical slideways, a glass light in each slide-way, and means for independently changing the positions of the lights in their respective slideways.

In testimony whereof I affix my signature.
THOMAS B. LAYCOCK.
